UNITED STATES PATENT OFFICE

GEORGE T. RONK, OF CEDAR RAPIDS, IOWA

SELF-LOCKING BOOM HOIST

Application filed September 29, 1930. Serial No. 485,141.

This invention relates to improvements in excavating machinery in which is employed a pivotally mounted boom to swing in a vertical plane and mechanism for elevating and lowering the free end of the boom.

The object of my invention is to provide a simple, durable and inexpensive device for elevating and lowering the free end of the boom, whereby the free end of the boom will be automatically supported against rapid downward movement in the event of disconnection or failure of the power to elevate the boom; and to provide in connection therewith hand actuated means whereby the boom may be easily and quickly manipulated to lock the boom in any of its elevated positions.

More specifically it is the object of my invention, to provide in connection with a boom hoisting mechanism, including a rotatively mounted cable drum adapted to be operated in one direction for hoisting the boom and operated in the opposite direction as the boom is moved to its lower position of movement, means actuated by the reverse movement of the cable drum for retarding the lowering action of the boom, whereby the boom may be lowered at a comparatively slow speed and by gravity alone, without the use of reverse power mechanism; and to provide in connection therewith means for locking the boom against downward movement at the will of the operator, and when the boom is in any of its vertical swinging positions of movement.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of a segmental portion of an excavating mechanism and a pivoted boom showing the manner in which my improved locking mechanism is applied thereto.

Figure 2 is a detail sectional view taken on the line 2-2 of Figure 1.

Figure 3 is a detail sectional view taken on the line 3-3 of Figure 2.

Figure 4 is a detail sectional view taken on the line 4-4 of Figure 2.

Figure 5 is a detail sectional view taken on the line 5-5 of Figure 3.

Referring to the accompanying drawing, I have used the numeral 10 to indicate an excavator platform of ordinary construction and designed to be rotatively mounted about a vertical axis on an excavator truck not illustrated.

The platform 10 is provided with a boom 11 pivotally mounted thereto by a pivot 12. The free end of the boom is designed to swing in a vertical plane. The platform 10 is provided with frame members 13 in which is rotatively mounted a shaft 14. Said shaft is rotatively mounted in bearing members 15 and 16. One end of the shaft 14 has a cable drum 17 provided with a cable 18, one end of which is connected to said drum and the opposite end passed over a pulley 19 carried by the free end of the boom 11, and then returned to a fixed point 20 carried by the frame member 13.

By this arrangement it will be seen that rotation of the drum 17 in one direction will cause the free end of the boom 11 to be elevated, and that the weight of the free end of the boom will cause the drum to be operated in the opposite direction when the power for rotating said drum is disconnected. The boom is provided with the ordinary bucket 21.

For rotating the drum 17 and winding the cable 18 to elevate the boom, I have provided on the opposite end of the shaft 14 a clutch member 22 permanently keyed to said shaft. A coacting clutch drum 23 is mounted on a sleeve 24, the inner end of which is connected to a gear 25 included in the usual train of transmission gears 26 and operated continuously in one direction. The clutch members 22 and 23, are closed and opened by means of a lever device 27 also of ordinary construction.

By this arrangement it will be seen that by manipulating the coacting clutch members 22 and 23, the shaft 14 may be rotated to

wind the cable 18 and to elevate the free end of the boom.

For locking or retarding the downward movement of the free end of the boom, I have provided the following mechanism. The drum 17 is provided with a flange 28 to which is secured a spring actuated pawl 29 designed to coact with a ratchet wheel 30 supported by a sleeve 31 and rotatively mounted in the bearing member 16. The inner end of the sleeve 31 is provided with a worm gear 32 designed to coact with a worm 33 mounted on the upper end of a vertically arranged shaft 34. Said shaft 34 is rotatively mounted in a housing 35. The lower end of the shaft 33 is provided with a brake drum 36 having a brake band 37 designed to be operated by a lever device 38 of ordinary construction. The lever 38 is controlled by a rod 39 provided with suitable lever arrangement including means for locking the band 37 in a closed position.

By this arrangement it will be seen that as the shaft 14 is rotated in an anticlockwise direction, as viewed in Figure 1, the cable 18 will be wound and the free end of the boom 11 elevated. Releasing the clutch members 22 and 23 will stop the elevation of the said boom and the drum 17 will be rotated in a reverse direction by the weight of the said boom, causing the pawl 29 to engage the ratchet teeth of the ratchet 30, which in turn will cause the sleeve 31 to be rotated, together with the worm gear 32. Said gear 32 causes the worm 33 and the shaft 34 to be rotated. The gear ratio of the said worm gear is such that the free end of the boom will be permitted to descend slowly.

The speed ratio of the worm gear and its coacting worm is such that the weight of the boom 11 will cause the worm 33 to rotate at a comparatively slow speed without locking the boom against downward movement, which in actual practice is somewhat less than 32 to 1, as ratio above 32 to 1 under ordinary operating conditions will automatically lock the boom against downward movement.

I am well aware that worm gears have been provided for driving the boom elevating drum in both directions. The gear ratio is such that the boom is locked against downward movement when power is disconnected from the worm, and thereby providing means for automatically locking the boom against lowering.

I find in actual practice, however, that this arrangement is objectionable in that the gear mechanism for driving the worm must operate at a high speed, which results in considerable loss of power, due to friction, and furthermore, reverse mechanism must be provided for lowering the boom, which adds considerable to the weight of the machine and to the expense.

In my improved hoisting mechanism the ordinary spur gear drive is provided for elevating the boom by rotating the cable drum in the usual manner. The loss of friction due to this arrangement is reduced substantially to a minimum. The lowering of the boom is automatically controlled by very simple and effective ratchet and worm gear arrangement, no power being required from the power device. Means is provided in the drum 36 and the brake band 37 for locking the worm shaft 34 against rotation and the boom against lowering.

On account of the high speed ratio between the worm and worm gear, it will be seen that a comparatively small amount of power is required for locking the shaft 34, which results in a locking device which may be easily controlled by the operator.

While my improved hoisting mechanism is illustrated as being applied to elevate and lower the free end of an excavator boom, it will readily be seen that the same mechanism might be applied to any cable drum in which the weight is suspended directly from the cable wound thereon.

Furthermore, the clutch mechanism illustrated is hand controlled, while it will readily be seen that a mechanically controlled clutch device might be substituted such as in common use on excavating mechanism.

Thus it will be seen that I have provided a hoisting mechanism of simple, durable and inexpensive construction, in which a minimum amount of power is required for operating the hoisting drum, and in which the excessive downward movement of the weight carried by the drum cable is automatically controlled, and in which all power for the operation of the device, as the weight is being lowered, is limited.

I claim as my invention:

1. In combination, a cable drum, a clutch controlled mechanism for imparting winding movement to said drum, a worm gear mechanism for retarding the unwinding movement of said drum, means actuated by the reverse movement of said drum for automatically connecting said worm gear mechanism to said drum.

2. In combination, a cable drum, a clutch controlled mechanism for imparting winding movement to said drum, a worm gear mechanism for retarding the unwinding movement of said drum, means actuated by the reverse movement of said drum for automatically connecting said worm gear mechanism to said drum, a brake drum operatively connecting the driven member of said worm gear mechanism, and hand controlled brake band for said drum.

3. In combination, a cable drum, a driving gear, a clutch for operatively connecting said gear and said drum, worm gear speed retarding mechanism, a ratchet device for oper-

atively connecting said worm gear mechanism to said drum upon reverse movement of said drum.

4. In combination, a cable drum, a cable connected to said drum, a driving gear, a clutch for operatively connecting said gear and said drum, worm gear speed reducing mechanism, means for operatively connecting said worm gear mechanism to said drum upon reverse movement of said drum, the speed ratio of said worm gears being such that the drum will be unwound at a comparatively low speed and by weight applied to said cable.
